UNITED STATES PATENT OFFICE.

ALBERT RUSH, OF COLUMBUS, OHIO.

DOOR FOR ELEVATOR SHAFTS.

1,341,863.

Specification of Letters Patent.

Patented June 1, 1920.

Application filed September 22, 1919. Serial No. 325,444.

To all whom it may concern:

Be it known that I, ALBERT RUSH, a citizen of the United States, residing at Columbus, in the county of Franklin and State 5 of Ohio, have invented a certain new and useful Improvement in Doors for Elevator-Shafts, of which the following is a specification.

The present invention relates to the type 10 of elevator and door shown in the patent issued to me September 9, 1919, No. 1,315,795 and has for its object a modification affording advantages in some respects, one of which is that door channels in the building 15 can be dispensed with.

Like the construction of my said former patent the present invention includes a support for the door on the car and in addition thereto, as distinguished from my 20 former construction, it includes a guiding channel for the door on the car, said channel leading to the door support on the car. Further the channel is of such construction as to permit the passage of the car past the 25 closed door when it is not desired to stop the car at the door.

The invention is embodied in the construction herein shown and described, the features of novelty being finally claimed.

30 In the accompanying drawing—

Figure 1 is a vertical sectional view through the car and door showing their relation to the floors of a building at the elevator well.

35 Fig. 2 is a horizontal section on the line II—II Fig. 1, looking down.

In the views 5 designates the several floors of a building adjacent the elevator shaft or well and 6 an opening or doorway 40 to such shaft. Each opening 6 is provided with a door like that shown at 7 adapted to be raised and lowered, the door being provided with suitable counterbalancing means if desired, to facilitate the operation.

45 The car or carriage has secured to each of its opposite sides by suitable brackets 8 a vertical guiding channel 9 extending substantially the full height of the car. The upper end of channel 9 is prolonged and 50 flared for a portion of its length above the car so as to form a guide and support 10. The upper end of the flared portion of the guide above the car is left with an opening 10^a in one of its walls in vertical line with 55 the channels 9 so as to afford an unobstruct-

ed passage in a vertical line for a stud roller as hereinafter described.

Each of the doors has on the room side hooks 12 to take into sockets 13 when the door is closed and therefore prevent face-wise movement of the door but permit it to be raised in a vertical direction. On the well side of the door at its upper and lower corners are projecting arms 14 having projecting lateral studs 15 bearing rollers 65 adapted to enter the channels when the car is brought opposite the door, as shown in Fig. 1.

When the car is brought opposite the door and stopped the channels on the car serve 70 as guides for directing the door to the support on the top of the car as shown in broken lines Fig. 1. On the other hand the openings 10^a in the flared portions of the channels permit the car to move past the door 75 without disturbing the door at all.

The car will, of course, be provided with any suitable means for hoisting it.

The forms of the parts can be changed without departing from the invention as 80 claimed.

What I claim is:

1. The combination with a building having an elevator shaft and doorways leading from the floors of the building to the shaft 85 and a car to move vertically in said shaft, of sliding doors for the doorways of the building, a support on the car to receive one of said doors and guiding means on the car below said support to guide the door to 90 said support.

2. The combination with a building having an elevator shaft and doorways leading from the floors of the building to the shaft and a car to move vertically in said shaft, of sliding doors for the doorways of the building, a support on the car to receive one of said doors and channels on the car below said support to guide the door to 95 said support.

3. The combination with a building having an elevator shaft and doorways leading from the floors of the building to the shaft and a car to move vertically in said shaft, of sliding doors for the doorways of the 105 building, a support on the car to receive one of said doors, guiding means on the car below said support and means on the door to engage said guiding means to direct the door when raised to the support. 110

4. The combination with a building having an elevator shaft and doorways leading from the floors of the building to the shaft and a car to move vertically in said shaft, 5 a support on the car to receive one of said doors and guides on the car below said support to guide the door to the support, said guides constructed to permit the car to pass the door when closed without disturbing the 10 same.

5. The combination with a building having an elevator shaft and doorways leading from the floors of the building to the shaft and a car to move vertically in said shaft, 15 of sliding doors for the doorways of the building, a guide on the car extending above the top of the car where it forms a support for one of said doors when opened, means on the door for engaging said guide, said

guide provided with an opening permitting 20 the passage of the car past the door when in closed position.

6. The combination with a building having an elevator shaft and doorways leading from the floors of the building to the shaft and a car to move vertically in said shaft, of sliding doors for the doorways of the building, a guide on the car extending above the top of the car where it forms a support for one of said doors when opened, 30 means on the door for engaging said guide, said guide provided with an opening permitting the passage of the car past the door when in closed position and latching means for preventing facewise movement of the 35 door when in closed position.

ALBERT RUSH.
